UNITED STATES PATENT OFFICE.

JOHN W. HEDENBERG, OF CHICAGO, ILLINOIS.

IMPROVEMENT IN BALE-TIES.

Specification forming part of Letters Patent No. **146,529**, dated January 20, 1874; application filed July 23, 1873.

To all whom it may concern:

Be it known that I, JOHN W. HEDENBERG, of Chicago, in the county of Cook and State of Illinois, have invented an Improvement in Bale-Ties, of which the following is a specification:

The nature of the present invention consists in a buckle-plate, provided at one end with a folded-under part, between which and the buckle-plate the bent end of the strap-iron is held in place irrespective of the pressure of the cotton, the opposite end of the strap-iron being looped to the buckle-plate in the ordinary manner, as hereinafter fully described and shown.

In the drawing, Figure 1 is a top or plan view of my improved bale-tie, showing the two ends of the strap-iron; Fig. 2, an edge view of the same; Fig. 3, a half-sized view of the buckle-plate as it is cut from sheet metal; Fig. 4, a half-sized view of the buckle-plate, with its end doubled under to receive the strap-iron.

A represents the buckle-plate, which is first, by suitable dies, cut in the form shown in Fig. 3, E and F being holes through the plate to form bars H G I. The line *n* denotes a cut through the plate to enable the loop J B to be formed by bending it under the plate A, as shown in Figs. 1, 2, and 4. The buckle-plate thus formed is ready to receive the single strap-iron, whose ends are shown at C D. For general use the end C is put over the bar H, over the bar G, and then bent back between the bars, as shown at K, Fig. 2, the cap K being from two to six inches long. The opposite end D is bent under, as shown

at L, Fig. 2, so as to lap back an inch and a half, or thereabout, and the lap so formed is hooked over the bar I and put between it and the looped plate J B.

In practice, the strap-iron may be cut of such length as will wrap bales in any particular press, in which case the strap-iron is laid in the press in the usual manner, and, after the bale has been pressed, the looped end L is hooked in between the bar I and plate J B. The bale can then be removed from the press, and the loop J B will hold the bent part L firmly in place.

It will be seen from the shortness of the part L that after it is locked in the buckle the slack of the band and expansion of the bale can be but nominal, and not so much as to cause a waste of pressing power, as would be the case if the part L was lengthened out sufficiently to hold by friction of the cotton without the aid of the loop J B; and, further, that the peculiar form of cut *n*, when the part J B is bent on dotted lines S, causes the part B to project beyond the buckle-plate A, and thus form a continuous support for the loop L, whereby the use of material is economized, inasmuch as the loop L may be very short.

I claim and desire to secure by Letters Patent of the United States—

The buckle-plate A, provided with the bars H G I, in combination with the looped plate J B, constructed substantially as and for the purpose set forth.

JOHN W. HEDENBERG.
